CLAIM

The ornamental design for the combined nipple and ring, as shown and described.

DESCRIPTION

FIG. 1 is a perspective view of a combined nipple and ring, showing my new design;
 FIG. 2 is a front elevational view thereof, the rear elevational view thereof being identical;
 FIG. 3 is a side elevational view thereof, with the opposite side view being identical;
 FIG. 4 is a top view thereof; and,
 FIG. 5 is a bottom view thereof.
 The broken line showing of the letters and number in FIGS. 1 and 2 is for illustrative purposes only and forms no part of the claimed design.
